SWAB CONSTRUCTION

John Charles Trindl, Chicago, Ill.

Application May 28, 1942, Serial No. 444,851

2 Claims. (Cl. 15—229)

My invention relates to an improved swab construction and is directed more particularly to such a construction which may be used by the housewife in either wet or damp condition without necessitating the handling of the swab head throughout the wetting, cleaning and water extraction operations.

An important object of the invention is to provide a swab body which is made up principally of a multiplicity of strands so disposed upon a rigid backing member that they are positioned in predetermined zones over the face of the backing member, retain those zones over the face of the backing member, and retain those zones in a controlled manner throughout the soaking of the swab and throughout the use thereof in cleaning and water extraction operations.

Still another object of the invention is to provide a construction of the above character in which the pliant strands are disposed in groups which occupy predetermined zones, certain of these groups providing a matted base for others of the group, whereby each group is compacted against adjacent groups in such a manner that they may be easily separated after the cleaning operation, each then occupying its predetermined zone after the separation, to greatly facilitate the quick drying of the swab.

Still another object of the invention is to provide a construction utilizing pliant, fabric strands which are so arranged that the heretofore objection of "slopping" is avoided and whereby the user can accurately control the strands to clean a predetermined area or surface without portions thereof, particularly the ends, contacting adjacent surfaces which are not susceptible of being cleaned by the use of such a device.

Another important object of the invention is to provide a swab construction from which the liquid or fluid may be quickly and easily extracted without necessitating any special drainer construction and without necessitating the contact of the hands of the user with dirty water.

A further object of the invention is to provide a novel rigid backing member for a swab construction of the above character in which is incorporated a curved attachment surface for greatly augmenting the liquid extraction operation when it is performed by urging the assembly against a slightly curved or even a flat surface.

It is a more specific object of the invention to provide in a swab construction, a rigid backing member having a lower attachment surface and a plurality of strand assemblies attached thereto, said assemblies including independent units com-

prising rows of pliant strands held together between strips of fabric which are stitched together and through which retaining nails are driven, the opposed ends of the strands being so disposed that they extend outwardly of the surface of the backing member to lie adjacent one another, each length of outwardly disposed strands being compacted against the adjacent group of strands to provide a compacted mass over the attachment surface of the backing member.

In accordance with the general features of my invention there is provided herein a construction which includes a rigid backing member constructed to present either a flat or a transversely convex attachment surface (both being satisfactory but the latter being preferred), a plurality of pliant, liquid absorbing assemblies protruding from the attachment surface, the protruding portions being compacted one against the other and being disposed and retained in predetermined zones on the surface whereby the strands in one zone do not become enmeshed or "balled" with strands in an adjacent zone and whereby longer central strands may be compressed against adjacent shorter strands for liquid extraction without becoming entangled with those shorter strands and without being pressed out of the confines of the backing member by which extraction pressure is applied thereto.

Many other objects and advantages of my invention will become apparent from the following description and accompanying drawings, in which:

Figure 1 represents a fragmentary plan view of a strand unit adaptable to a swab construction embodying the features of my invention.

Figure 2 is a similar view of still another strand unit embodying my invention.

Figure 3 is a cross-section view taken on the line III—III of Figure 1.

Figure 4 is a fragmentary cross-sectional view taken on the line IV—IV of Figure 1.

Figures 5 and 6 represent transverse cross-sectional views of a swab head embodying one form of my invention.

Figure 7 represents a transverse cross-sectional view embodying a modified form of my invention.

Figure 8 represents a cross-sectional view showing still another modified form of my invention.

Figure 9 is a side elevation, on a reduced scale, of a swab head embodying the features of my invention; and

Figure 10 is a transverse cross-sectional view of a swab embodying my invention after it has been subjected to water or other cleansing fluid

and after it has been used for cleaning purposes and subject to compression for water or fluid extraction therefrom.

It will be understood that the embodiments disclosed herein are for illustrative purposes only and may be changed or modified without departing from the spirit or scope of the invention as set forth in the appended claims.

In the past, mops constructed from pliant fabric strands have been deemed to necessarily include strands of extremely great length in order that the desired liquid absorption qualities be provided, in order that a relatively long life be imparted to the mop assembly, and in order that they could be wrung out by hand or by a mop wringer mechanism. This construction was found to be necessary in the past because the pliant strands were clamped tightly in a rigid holder having jaw-like elements and when thus clamped, protruded from the jaw-like elements as a relatively thin stack or group of strands. It will be understood that the water or liquid absorption qualities of any cleaner utilizing a fabric material will be proportional to the amount of such material employed in that construction. I have found that if a rigid backing member is provided and the strands are secured thereto in accordance with my invention so that they are tightly compacted, then sufficient of these strands are provided for imparting the desired absorbent qualities to the structure. In other words, while in the past, the length of the strands has contributed to the liquid absorption qualities, I have provided a novel swab construction wherein compacted and controlled strands give this quality and also present many additional advantages.

In the conventional mop structure heretofore used the length of the strands is such that their disposition and travel over the area to be cleaned is only generally controlled by the movements of the mop handle by the user, and when cleaning in corners, around mop boarding where painted or papered walls are adjacent thereto, or when cleaning relatively small areas, the major portion of the strands move only through a general arcuate path in response to the movement of the handle, and in addition to this arcuate path the strands each travel in an uncontrolled manner through minor arcuate paths about the jaw-like holding members, this latter movement being a result of the momentum produced by the general arcuate movement of the mop handle. Under such circumstances, the excess water is deposited on surfaces other than that which are intended to be cleaned with the result that those surfaces are left in such condition that further cleansing thereof is necessary if the surface has not been permanently defaced by the liquid and dirt applied thereto.

Another detriment attending the use of the conventional type of mop is that the long strands, in order to have the excess fluid extracted therefrom for "damp cleaning" must either be wrung out by the user, which, of course, involves the contact between the hands and dirty water or requires the use of complicated rolling or water-extracting mechanisms for the drying operation.

Referring to the drawings, particularly to Figure 5, the rigid body portion of the swab includes a block member 10 made from wood or the like which may be provided with a handle receiving orifice 11 disposed angularly therein. The bottom surface 12 of the rigid backing member constitutes an attachment base for the swabbing material and may be made flat as shown in Fig-

ure 6 or rounded as shown in Figure 5. As previously stated, the rounded surface is preferred since it greatly facilitates the extraction of moisture from the device as will be described presently.

The unit containing the pliant strands may take many different forms. However, in the preferred embodiment they constitute assemblies such as those shown in Figures 1, 2, 3 and 4. In those figures, it will be seen that the strands of absorbent material such as cotton or the like, are retained in plate-like stacks by means of fabric retaining members 14 which comprise tape-like members between which the strands 13 are held and compressed centrally by stitches 15. It will be understood that when the members 14 overlie and underlie the groups of strands 13 and are stitched as at 15 a unitary structure is provided which comprises portions securely attached together which may be readily handled during manufacturing and assembly operations.

Two types of units of the character of those described above are preferably utilized in making the structure shown in Figure 5. The unit shown in Figure 1 has the ends of the pliant strands sheared so that they protrude in different lengths from each side of the retaining member 14. As will be seen presently, the ends 13a are so arranged on the rigid back member 10 that they extend over the respective longitudinal edge thereof while the longer ends 13b are disposed in such a manner that they lie adjacent the ends 13a. The unit shown in Figure 2 includes the retaining member 14 and the protruding group of strands 13, the ends 13c thereof extending from the retaining member 14 in opposite directions and in equal lengths, each of these lengths being preferably equal to slightly more than one-half of the total width of the attachment surface 12 of the block 10. It will be understood, of course, that the thickness to which the strands 13 are stacked between the members 14 and the length of the strands used depends entirely upon the size of the rigid backing members on which they are to be stacked, it being preferable, however, that each layer of strands 13 be sufficiently thick so that the ends thereof flare outwardly and laterally a sufficient amount to provide compacting of the groups of strands one against the other when they are assembled upon the backing member as shown in Figure 5.

In the construction shown in Figure 5, strand units such as that shown in Figure 1 are secured longitudinally of the surface 12 and in surface engagement therewith in the vicinity of the respective longitudinal edges thereof by suitable attachment means such as nails 16. Thus it will be seen that the fabric or tape members 14, together with the strands compressed therebetween by the stitching 15, serve admirably as anchoring means by which the respective units can be securely attached to the rigid backing member 10. As shown in Figure 5, the shorter strands 13a are disposed to extend somewhat beyond the longitudinal edges of the surface 12, yet not to such a degree that they do not respond directly to movements of the backing member 10, while the opposite ends 13b are bent back upon the ends 13a to underlie the same and to compress these ends 13a into a compacted unit.

In the form of my invention shown in Figure 5, the structure is completed by wedging a strand unit such as that shown in Figure 2 between the upturned ends of the retaining tapes 14 of the side units. In the same manner that the

roots of the various units are retained in wedging engagement, the outer ends thereof are likewise compacted into a dense arcuate configuration by the flaring of the end portions 13c of the latter units whereby those portions are compressed together and, on their outer sides, are compressed against the ends 13b previously described. The central strand unit is securely retained in this wedging position by means of suitable nails 17 or the like.

As previously explained, should the strands become knotted or enmeshed with one another to too great a degree the efficiency of the completed structure is affected detrimentally as to the water retaining qualities as well as to the cleaning and water extraction characteristics. Thus it is necessary that the various zones of strands be disposed in an orderly fashion during the manufacturing operation and also be so secured to the rigid backing member 10 that these zones are retained in an orderly manner during the cleaning and the liquid extraction operations.

It will be understood that in using a swab such as that shown in Figure 5 the strands, there shown, will become somewhat condensed and compacted inwardly and upwardly toward the surface 12 as is shown in Figure 10; thus they will present a cleaning surface which possesses dimensions somewhat similar to the dimensions of the surface 12.

When the strands are so compacted, it is found that the ends 13a still project from the outer confines of the surface 12 thus to provide a bumper which prevents injury to furniture and mop boarding when the swab is being applied to surfaces adjacent thereto. In this compacted condition the strands 13c which, as previously explained, are somewhat longer than the strands 13a and 13b, will be compressed so that they are compacted against one another and against the ends 13b which in turn are then compressed against the ends 13a. The compression of each succeeding group or unit prevents the strands of adjacent groups or units from becoming enmeshed therewith, whereby the entire strand assembly, while it is in this somewhat compressed condition, still is so arranged that the various different sets of ends are each retained generally within their predetermined zones as shown in Figure 5.

Furthermore, it will be seen that because of the adjacency of the overlying units of strands, each unit, though having strands of a length sufficient to extend considerably over the longitudinal edge of the surface 12, and even perhaps to the upper edge of the surfaces 10a, will be prevented from doing so because of the obstruction afforded by the adjacent unit of strands disposed upwardly thereof. In other words, each strand of each unit is prevented from being disposed or extending directly toward the outer confines of the rigid backing member 10 by the next adjacent outwardly disposed unit which affords an obstruction about which it must curve whereby its length in excess of the distance of the longitudinal edge of the surface 12 is consumed by being disposed in a substantially arcuate path.

In view of the foregoing, the central strands 13c may be of such a length that, if unobstructed, by the overlying units 13b and 13a, they would extend beyond the upper edges of side walls 10a and thus be unavailable for liquid extraction by pressure exerted on the rigid body member 10.

With such a construction, as will be seen from Figure 9, the resulting compressed mass of

strands, even though they have been wetted, will maintain the general configuration of those shown in Figure 5 and thus if the backing member 10 is pressed against the flat surface with the surface 12 downwardly and is then rolled back and forth, the various strands are compressed one against the other in such a manner that all of the strands will be effectively squeezed to provide relatively complete extraction of liquid therefrom. Figure 9 represents the condition of the soaked strands as the backing member 10 is urged downwardly. The strands 13c have begun to collapse and from this figure it will be understood that if the backing member is rocked transversely the strands 13c will be compressed in an orderly fashion against units 13b which will compress strands 13a which in turn will be fully compressed by the surface 12. The efficiency of the resulting liquid extraction and the ease with which it may be accomplished will be readily apparent since the central strands and units 13b and 13c are retained in the confines of the surfaces 12 and 10a due to their arcuate disposition. This has been found to be one of the important advantages of the construction embodying my invention since ordinarily such complete extraction of liquids can be obtained only by complicated mechanical devices or by the use of the hands which is found to be thoroughly objectionable to the average user.

As previously explained, during the extraction operation all of the strands are effectively squeezed since those at the central portion, groups 13c, will be compressed against the surface 12 at the center thereof while the succeedingly outwardly disposed strands are compressed progressively against each other and against the strands 13a which are in turn compressed against the surface 12 and the sides 10a of the backing member 10 when the latter is rolled back and forth by the manipulation of a handle fitted into the aperture 11.

It will be understood that in constructions wherein the strands become knotted, enmeshed with one another or "balled," the extraction operation is very inefficient since the mop becomes bumpy and certain portions are protected by these bumps and then retain liquid throughout the extraction process. Furthermore, when such enmeshing of the strands occurs, the efficiency of the cleaning operation is very detrimentally affected. In the present construction, however, it will be seen that the longer strands 13c, which are highly important in the cleaning operation and in maintaining the life of the construction, are maintained in an orderly predetermined arrangement due to the control which is obtained by the canvas or fabric retaining members 14. It is also to be noted that the control of direction of the various strands is enhanced to a great degree by the wedging action which occurs between the various units. For instance, the strands 13b of the side sections are effectively retained in their laterally disposed positions adjacent the strands 13a by means of the compressing action of strands 13c which in turn are wedged between each other and the adjacent set of strands 13b to be retained in their central position.

Swabs constructed in accordance with my present invention and which have been used for the normal life of a device of this character and which have been used under all normal conditions have been found to retain the various strand zones shown as in Figure 5 and Figure 10.

It is found that if a pencil is extended between any one set of strands and then run longitudinally of the backing member 10, the very definite original parting is still clearly retained and none of the strands have become entangled or enmeshed with strands of the adjacent zones. Furthermore, it is found that the strands within each zone are free of entanglement with one another due to the relative short lengths thereof.

In practice, it has been found that if, after rinsing, the construction shown in Figure 5 is rolled as above described against a flat surface or the corner junction of the two flat surfaces to obtain the desired water extraction, and then the backing member is tapped on one or both of its ends, that the strands are shaken entirely loose from one another, the zones are clearly defined, and thus air permitted to circulate freely through the cleaning assembly to effectively and quickly dry the same.

From the foregoing, it will be seen that I have provided a swab construction which embodies soft, pliant cleaning strands of a length sufficient to provide effective cleaning and liquid absorbing qualities and yet are short enough to afford precision cleaning and efficient liquid extraction which is so constructed and arranged that the strands are disposed at all times in a controlled manner in separated zones. This controlled disposition of the strands effectively enhances the water extraction process and prevents the strands from becoming enmeshed or "balled" to render the swab construction ineffective for the purposes desired.

If a swab construction in accordance with my invention is to be used in particularly heavy work, that is, where more abrasive surfaces are to be cleaned or where higher liquid absorption qualities are desirable, an increased compacting of the strands may be obtained by increasing the number of central zones of long strands indicated at 13c in Figure 5. Such a construction is shown in Figure 6 of the drawings which is similar to Figure 5 except that a plurality of central units such as those shown in Figure 2 is utilized.

It will be noted that in the constructions of both Figure 5 and Figure 6 a degree of spacing is shown at the heads of the nails 16 and 17 and between the various zones. It is found that this condition prevails in a newly manufactured unit which has not yet been subjected to liquid cleansing material. However, after the unit has been soaked it is found that the strands, as previously explained, tend to compact inwardly and upwardly whereby a solid cleaning agent is presented as shown in Figure 10.

As shown in Figure 6 the surface 12 is formed flat. Such a surface tends to increase the compacting between the various zones or strands. However, it will be readily understood that in the liquid extraction operation a greater degree of rocking motion is required to effectively extract excess fluid from the strands than is required with the rounded surface such as that shown in Figures 5, 7 and 8.

As stated above, swabs of the character here disclosed are often utilized in heavy duty work where highly abrasive surfaces such as rough concrete and the like are encountered. Such surfaces cause considerably rapid wear of unprotected strands, and to the end that the strands may be protected from excess wear under such conditions, a construction such as that shown in Figure 7 may be utilized.

In this form of the invention, the members

14a instead of being narrow as heretofore shown, are in width substantially equal to the length of the respective strands. As used in the constructions of Figures 5 and 6, the members 14 are not subjected to abrasion and are employed merely as retaining elements or anchoring elements for the various groups of strands and therefore the fabric from which they are constructed need not be unusual strength. In fact, if desired, the strands of Figure 5 may be merely stitched, cemented or the like, so long as the desired compacting of the roots is obtained. However, in the construction of Figure 7, these members actually serve as protective elements for the side portions of the units or zones of strands, and therefore it is preferable that they be made of heavy duck or canvas.

As in the constructions of Figures 5 and 6, the modification in Figure 7 is so arranged that the various layers of strands are compressed against one another and so that they retain this relationship during the liquid extraction and cleaning procedure.

In the modified form of the invention shown in Figure 8, there is provided a combination cleansing element which utilizes a central sponge-like element 18 which is provided with tape-like members 19 and 20 which, in turn are stitched centrally and longitudinally thereof as at 21 or, if desired, may be glued thereto. In the past, it has been the custom to glue sponge-like material such as sponge rubber or cellulose sponge to the rigid backing member 10. However, when constructed in accordance with my invention, that is, with the member 20 glued or sewed thereto, it is found that a strong central attachment assembly is provided whereby the nails 22 securely retain the member 18 upon the backing member 10.

On each side of the centrally disposed member 18 there is provided a fabric strand construction similar to that disclosed in Figures 5, 6 and 7. Preferably, however, the strands 13b are of such a length that they overhang the member 18. With this construction, it is found that the central member has high liquid absorbing qualities while the fabric strands 13a and 13b provide the desired cleansing qualities. Furthermore, the member 18 which is highly subject to deterioration by abrasion is substantially protected by the overhanging strands 13b which are disposed adjacent thereto. It will be understood, of course, that the water extraction procedure is performed as explained in connection with Figures 5, 6 and 7 and that furthermore, the various layers of liquid absorbing and cleaning material will be successively pressed against one another progressively toward the outer zones so that efficient extraction of the liquid takes place.

From the foregoing it will be seen that there has been provided herein a swab construction which utilizes a rigid backing member and a plurality of cleaning members disposed to occupy definite, predetermined zones, the latter members including strands which are provided with attachment means so arranged that the direction in which the strands extend is controlled and predetermined whereby they are prevented from becoming enmeshed with one another to reduce the efficiency of the mop. Furthermore, the disposal of the various zones of strands, or in the case of Figure 8, zones of strands and sponge material, is such that the various groups occupying the different zones are compressed one against the other progressively toward the out-

side during the liquid extraction operation whereby each of the strands is effectively subjected to liquid extraction by squeezing and thus the liquid extraction operation is completed with efficiency. It will also be noted that the disposal of the inner units and strands is such that they may be of considerable length without extending beyond the ends of the strands 13a during the extraction and cleansing operations, and yet they are prevented from becoming "balled" and thus rendering the cleaning and liquid extraction operations less efficient. There is also provided a swab construction in which the strands are so arranged that they are disposed to form a bumper along the edges of the rigid backing member, thereby to prevent the latter from injuring woodwork and further serving as an aid to the cleaning of close quarters such as corners or the like.

There is also provided a swab construction in which is incorporated a novel and economical attachment arrangement which effectively holds the strands in secure attachment to the rigid backing member.

As previously mentioned, the cleaning operation as performed by a swab of the construction shown herein is much more convenient and much more under the control of the user than is the case with the conventional mop having extremely long strands. With the present construction the strands extend merely over the attachment surface of the rigid backing member and are tightly compacted thereon, whereby the user is in complete control, at all times, of the action of the various strands merely by moving the rigid backing member the desired distances and in the desired directions. Thus a more precise cleaning operation may be performed with the present construction.

With regard to the manner of attachment of the various groups of strands to the lower surface of the rigid backing member, it is to be noted that the various lengths of strands or, in the case of Figure 8, the strip of cellulose sponge or the like, are tightly compacted at intermediate portions by means of the retaining strips 14, or the like. This compacting of the strands at their substantial central portions provides a relatively solid, strong attachment portion for receiving the various nails or the like which are required in the attachment assembly. Furthermore, the central

compacted zones are relatively stiffer than the pliant outer ends of the strands, and, since they are formed into substantial U-shape and pressed close to one another at the roots of the strands, 5 it has been found that the control of the predetermined position of the outer ends of the strands is greatly enhanced. It is my belief that this root construction for the strands contributes considerably to the orderly fashion in which the outer ends of the strands are disposed.

I claim as my invention:

1. In a cleaning device for use with liquid cleaning agents, a backing member having an attachment and pressing surface for receiving a liquid absorptive cleaning assembly, said assembly including a plurality of elongated units of pliant fabric strands, some of which are shorter than the width of said attachment surface and some of which are longer than the first named strands, means for securing said units of strands longitudinally of said surface in compacted relationship at the secured portion thereof, said shorter strands being disposed in surface engagement with the longitudinal edge margins of said surface and the longer strands being disposed longitudinally of the surface and progressively toward the transverse center thereof so that the longest strands extend outwardly from substantially said longitudinal center of said surface and are maintained substantially within the confines of the attachment and pressing surface by said shorter strands.
2. In a cleaning device for use with liquid cleaning agents, a backing member having an attachment surface, a liquid absorptive cleaning assembly including a plurality of elongated units of pliant liquid absorptive cleaning material disposed longitudinally on said surface, certain of said units being disposed in surface engagement 25 with the longitudinal marginal edge portions of said surface, and others of said units having the roots thereof secured to said surface with the outer ends thereof extending outwardly of said surface, and sheets of pliant material having a 30 width substantially equal to the width of said units from the roots to the outer ends thereof disposed longitudinally of said surface with the inner edges thereof secured to said surface, said sheets being disposed between adjacent units.

50

JOHN CHARLES TRINDL.
